UNITED STATES PATENT OFFICE.

HARRY R. SHIFFER, OF BROWNSTOWN, PENNSYLVANIA.

TOOTHPICK HOLDER.

Application filed August 1, 1928. Serial No. 296,735.

This invention relates to special receptacles and more particularly to a device of this character for holding and dispensing tooth picks and similar articles.

5 One object of the invention is to provide a receptacle in which tooth picks may be stored and thereby protected from dust and kept sanitary.

10 Another object of the invention is to provide the receptacle with a cover having an outlet opening through which the tooth picks may pass one at a time and further to provide means within the receptacle for guiding tooth picks into position to pass through the outlet 15 opening in the cover.

Another object of the invention is to form the cover with tongues disposed about the outlet opening so that, while an end portion of a tooth pick may easily pass through the outlet 20 let, it will be necessary to grasp the tooth pick and draw it through the opening thereby preventing the tooth picks from freely sliding entirely through the opening when the receptacle is tilted. This prevents likelihood 25 of more than one tooth pick passing out of the receptacle when it is tilted and also prevents danger of the tooth picks sliding out of the opening and dropping upon a floor.

Another object of the invention is to provide 30 a holder of this character which may be easily refilled or so formed that it may constitute the initial container for the tooth picks and be discarded when emptied.

The invention is illustrated in the accompanying drawing, wherein

35 Figure 1 is a side elevation of the improved tooth pick holder;

Fig. 2 is a top plan view of the same;

40 Fig. 3 is a longitudinal sectional view through the tooth pick holder;

Fig. 4 is a transverse sectional view through the holder, and

45 Fig. 5 is a fragmentary longitudinal sectional view through a modified form of holder.

The receptacle 1 of the holder may be formed of glass, china or any other materials desired if it is to be refilled or it may be formed of paper upon which an advertisement may be printed if it is to constitute an initial container for tooth picks and be discarded when emptied. The receptacle is open at its top and consists of a bottom 2 having upstanding walls 3 about its margins.

55 While the receptacle has been shown circu-

lar in cross section, as shown in Fig. 3, it will be understood that it may be any shape in cross section desired. In Fig. 3, the walls of the receptacle have been shown externally threaded adjacent the open upper end of the receptacle, as indicated at 4, and this threaded upper end portion of the receptacle is screwed into the internally threaded annular flange 5 of a cover or top 6. The cover may be formed of metal or any other suitable material and is shaped to define a series of annular steps between the marginal flange 5 of the cover and an opening 7 which is formed centrally therein. It should also be noted that about the opening 7 which constitutes an outlet for tooth picks in the receptacle the cover has been cut to provide a number of tongues 8 which converge towards the opening, as shown in Fig. 2. It will thus be seen that, while the tapered end portion of a tooth pick 70 may easily slide through the opening, the larger portion of the tooth pick will not be allowed to freely pass through this opening and it will be necessary to grasp the protruding end of the tooth pick and draw it through 75 the opening. By this arrangement the tooth pick may be easily extracted after the receptacle has been inverted or tilted to a dispensing position but there will be no likelihood of tooth picks sliding freely through the opening and either too many tooth picks passing out of the holder or a tooth pick dropping from the holder upon the floor or into a dish 80 upon a table and thereby becoming soiled or wasted by not being used.

When the tooth pick holder is filled or only a few have been dispensed, they will easily be guided to the outlet opening by the steps of the cover but after a certain number have been dispensed they are liable to assume such 85 angular relation to the axis of the receptacle that they will not easily pass into the opening. In order to guide the tooth picks into proper position for passing through the opening, I employ strips 9 which are each of a width corresponding to the internal diameter of the receptacle and are preferably of a length somewhat shorter than the depth of the receptacle. These disks are disposed in crossed relation to each other and since each is formed with a 90 longitudinally extending slide 10 they may be interlocked in crossed relation to each other and fitted into the receptacle, as shown in Figs. 3 and 4. This divides the receptacle into four compartments to receive tooth picks and 105

110

when the receptacle is tilted a tooth pick in one of the compartments which is uppermost will be disposed close to the intersecting portions of the strips 9 and will be so disposed that its outer end will very easily pass through the outlet opening in the cover and can be grasped and the tooth pick entirely withdrawn. By this arrangement the tooth picks can be very easily dispensed even when only 10 a very few remain in the receptacle. Since the cover is threaded upon the receptacle, it can be removed and the receptacle refilled after it has been emptied.

Some may desire to employ the dispensing 15 receptacle as an initial container for tooth picks in which case the receptacle or body portion 1 will be formed of cardboard or a like substance which may have advertising matter printed thereon and the cover also 20 formed of cardboard or cheap metal and permanently attached to the receptacle. This form of the invention is illustrated in Fig. 5 wherein the cover is indicated by the numeral 11 and has its marginal flange 12 disposed about the open upper end of the receptacle 13 where it is glued or otherwise 25 permanently secured thereto. Strips 14, corresponding to the strips 9, are shown within the receptacle 13 and each is formed with a slide 15 so that the strips may be interlocked in the same manner as the strips shown in 30 Figs. 3 and 4. It should also be noted that, if desired, these strips may have their outer ends notched, as shown at 16, so that the tooth 35 picks may very easily pass through the opening 17 in the cover.

Having thus described the invention, I claim:

1. A tooth pick container and dispenser comprising a receptacle open at its upper end, 40 a head for the upper end of said receptacle having an outlet opening formed therein, and means in the receptacle to guide tooth picks out of the receptacle through the outlet consisting of strips extending longitudinally 45 within the receptacle transversely of each other and intersecting in alinement with the center of the outlet opening.

2. A tooth pick container and dispenser comprising a receptacle open at its upper end, 50 a head for the upper end of said receptacle having an outlet opening formed therein, and means in the receptacle to guide tooth picks out of the receptacle through the outlet consisting of strips extending longitudinally 55 within the receptacle, each strip being slotted from one end with the other strip fitting into its slot, the strips extending transversely of each other and at their intersection being alined with the outlet.

3. A tooth pick container and dispenser comprising a receptacle, a head for one end of said receptacle having an outlet opening formed therein, and strips extending longitudinally within the receptacle and terminating in spaced relation to the outlet, said strips intersecting each other in alinement with the outlet opening and adapted to guide tooth picks towards the center of the receptacle and out through the outlet.

In testimony whereof I affix my signature.
HARRY R. SHIFFER. [L. s.]
